UNITED STATES PATENT OFFICE.

ERNEST T. BECK, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A BASE FOR A FOUNTAIN-PEN HOLDER.

Application filed April 7, 1927. Serial No. 21,499. Term of patent 14 years.

To all whom it may concern:

Be it known that I, ERNEST T. BECK, a citizen of Germany, residing at Meriden, in the county of New Haven and State of Connecticut, have invented a new, original, and ornamental Design for a Base for Fountain-Pen Holders, of which the following is a specification, reference being had to the accompanying drawing, forming part thereof.

Fig. 1 is a top view of a base for fountain pen holders showing my new design; Fig. 2 is a side view of the same.

The ornamentation of the border extends entirely around the device.

I claim:

The ornamental design for a base for a fountain pen holder as shown.

ERNEST T. BECK.
